US0D1056368S

(12) **United States Design Patent** (10) **Patent No.:** **US D1,056,368 S**
(45) **Date of Patent:** **** Dec. 31, 2024**

(54) **TEAT CUP LINER HEAD FOR MILKING MACHINES**

(71) Applicant: **GEA Farm Technologies GmbH, Bönen (DE)**

(72) Inventor: **Thomas Grüter, Lippstadt (DE)**

(73) Assignee: **GEA Farm Technologies GmbH, Bönen (DE)**

(**) Term: **15 Years**

(21) Appl. No.: **29/921,106**

(22) Filed: **Dec. 14, 2023**

Related U.S. Application Data

(62) Division of application No. 35/515,865, filed on Sep. 6, 2022 (U.S. filing date under 35 U.S.C. 384), and having an international filing date of Sep. 6, 2022, now Pat. No. Des. 1,024,461.

(57) **CLAIM**

The ornamental design for a teat cup liner head for milking machines, as shown and described.

DESCRIPTION

FIG. 1.1 is a left side perspective view of a teat cup liner head for milking machines in accordance with the present design;

FIG. 1.2 is a right side perspective view thereof;

FIG. 1.3 is an end view thereof.

FIG. 1.4 is a first side elevation thereof.

FIG. 1.5 is a second side elevation view thereof; and,

FIG. 1.6 is a third side elevation view thereof.

The broken lines depict portions of the teat cup liner head for milking machines that form no part of the claimed design.

1 Claim, 6 Drawing Sheets
